UNITED STATES PATENT OFFICE

MATHIAS R. KONDOLE, OF LOWER MERION TOWNSHIP, MONTGOMERY COUNTY, PENNSYLVANIA

TAG ATTACHMENT

Application filed August 3, 1927. Serial No. 210,249.

My invention is designed to afford improved means for non-detachably securing a tag or seal to an article by providing the flexible cord used as a connector with one or more end tips or needles having their cord-engaging shanks provided with barbs bent therefrom so that the free ends of the barbs diverge from the cord when the latter is pulled in the direction of its axis. The shank of the tip is preferably rolled or crimped axially around the end of the cord and the free end of the tip, comprising the barb, extends away from the end of the cord as well as outwardly from the axis thereof. The provision of such bent barb 15 on a tip prevents manipulation thereof within the tag pocket by which the tip might be brought into alignment with the tag aperture and withdrawn from the tag pocket by a pull on the cord. The barb also prevents inadvertent withdrawal of the tip from the tag pocket, which sometimes occurs when the tip is inserted in the tag pocket without bending the cord and lies in alignment with the axis of the cord, particularly when the latter 20 is not sufficiently limp to cause the tip to fall to the desired transverse position and act as a cross bar in the tag pocket. The bent barb also tends to turn the tip into the desired cross-bar position in the pocket when the cord is pulled. The barb may diverge from the axis of the cord or shank at any desired angle or curvature and to any desired distance so long as the distance between the free end of the barb and the taut cord is greater than 25 the diameter or length of the tag aperture through which the cord passes into the tag pocket.

The characteristic features and advantages of my improvements will more fully appear 40 from the following description and the accompanying drawings in illustration thereof.

In the drawings, Fig. 1 shows broken sections of cord having metal blanks rolled thereon at spaced distances, the blanks being 45 adapted to be cut transversely to form tips on opposite ends of cord sections; Fig. 2 is a cord section with tips on the ends thereof provided with diverging barbs; Fig. 3 is an elevation of a tag with a cord tip partly inserted 50 therein; Fig. 4 is an elevation of a tag, with

part broken away to show the pocket and with a cord and tip inserted therein with the end of the barb engaging the edge of the pocket; and Fig. 5 is an elevation of a tag having the cord tip lying crosswise therein. 55

The cords employed for the attachment of nondetachable tags, and which may be made of yarn or flexible wire, preferably have tips or needles applied thereto by rolling on an uncut cord 1 suitably spaced blanks consisting of intermediate sections 2 which encircle and grip the cord, and pointed ends 3 lying parallel to but free from the cord. The individual cord sections are formed by cutting transversely through the sections 2 to produce a cord of suitable length with a tip on each end with the points extending toward each other and lying parallel with the axis of the cord. The pointed end of the tip facilitates penetration of the fabric to which a tag 60 is to be affixed and may be used to penetrate the tag material if an imperforate tag is used. Where, however, the edge of the tag pocket is perforated, the operatives not infrequently insert the tips into the tag pockets blunt end 65 first, and the tags sometimes drop off before the tips assume a transverse or cross bar position. Moreover, it is possible, with a little practice, to realign the free end of a tip with the tag aperture by pressing with the fingers 70 against the pocket walls to hold the outer extremity of the tip and pulling on the cord, and when the free end of the tip is aligned with the aperture the tip and cord may be readily withdrawn from the pocket and the 75 tag detached from the article. 80

In accordance with my present invention, the free end of each tip is bent outwardly from the shank 4 formed from one-half a section 2 and forms a barb or prong 5 diverging from the axis of the shank and taut cord, so that when the tip is inserted through the aperture 6 into the closed pocket 7 of a tag 8 it cannot be withdrawn either accidentally or purposely and the point of the 90 barb cannot be aligned with the aperture 6 by manipulation of the tip or pulling on the cord. Pulling on the cord causes the barb point to engage the edge of the pocket as indicated in Fig. 4 since the distance between 95 100

the cord and barb point is greater than the diameter of the aperture. If the pull on the cord be increased, the barb will either perforate the wall of the tag and indicate that it has been tampered with or deflect the tip crosswise as indicated in Fig. 5. Where the tag contains no preformed aperture 6, the point of the barb 5 may be used to perforate the tag material and the shank of the tip and the cord pushed in after the barb.

While the cords are preferably provided with a tip at each end thereof, it is obvious that one end of the cord may be tipless and permanently attached to the tag. Instead of the tag in itself forming the price ticket as illustrated, it may consist of what is commonly designated a seal uniting the ends of a cord threaded through an article and a ticket or the like having no pocket therein.

The barbs 5 are preferably bent outward from the intermediate sections 2 before they are severed to form shanks 4. They may be severed by an angular cut to provide pointed ends instead of, or in addition to, pointing the barb ends. The cords are preferably sufficiently limp to permit the ready bending thereof relatively to the tips at the points 9 intermediate the tip ends and the shank and barb are preferably of such relative weights as to turn readily to the cross-bar position shown in Fig. 5.

Having described my invention, I claim:

1. An attachment for a tag or the like comprising a flexible cord having fixedly secured thereon a tip comprising a shank sleeved on the cord coaxially therewith and a barb bent therefrom so as to diverge from the cord when the latter is pulled in the direction of its axis.

2. An attachment for a tag or the like comprising a flexible cord provided with an end tip fixedly connected thereto and having a body coaxial with the cord and a barb diverging from the body thereof and pointing away from the end of said cord, said cord being adapted to bend freely relatively to said tip at a point between the outer end of said tip and the end of said barb to form a cross piece preventing withdrawal of said cord from an apertured tag or the like.

3. An attachment for a tag or the like comprising a flexible cord having a tip rolled around its axis at an end thereof, said tip having a free portion removed from the end of the cord and diverging from the axis about which said tip is rolled so that when the cord is pulled in the direction of such axis said free portion projects outwardly therefrom.

4. An attachment for a tag or the like comprising a cord having on each end thereof a needle having a shank concentric with the axis of the cord, each needle having a point projecting away from the end of the cord to which the needle is fixed and each point diverging from the cord when the latter is in alignment with the shank of the needle.

5. The combination with an apertured tag, of a cord passing through the aperture of such tag and connected with a needle intermediate the ends of said needle, said needle having a body concentric with the axis of the cord and being adapted to form a cross pin preventing disengagement of said cord and tag and having a barb diverging from said cord when the body of the needle is disposed axially of said cord.

6. The combination with an apertured tag containing a closed pocket, of a cord passing through an aperture of said tag into said pocket and having a needle rolled thereon concentrically with the axis of the cord and with a free part diverging from the axis of said cord and adapted to engage a wall of said tag when the cord is pulled.

In witness whereof, I have hereunto set my name this 30th day of July, 1927.

MATHIAS R. KONDOLE.
